UNITED STATES PATENT OFFICE

THOMAS J. POWER, OF SYRACUSE, NEW YORK, ASSIGNOR TO UNITED STATES HOFFMAN MACHINERY CORPORATION, OF NEW YORK, N. Y., A CORPORATION OF DELAWARE

CYLINDER FOR WASHING MACHINES AND THE LIKE

Application filed September 16, 1931. Serial No. 563,176.

This invention pertains to an improved door construction and locking means therefor employed in connection with cylinders of washing machines and the like.

5 In modern washing machines the cylinders are sometimes quite long, and consequently it is advantageous, if not necessary, to employ a multiple-door construction for closing the opening in the cylinder through which the goods undergoing treatment are introduced and removed. It is likewise advantageous to have such opening entirely clear throughout its length when rugs and the like are being handled.

15 The main object of the invention resides in the provision of means whereby the doors when in open position are precluded from being interlocked, so that each door may be moved to its closed position independently of 20 the other.

Said means also includes the provision of a hinged division bar intermediate the adjacent ends of adjacent doors, which, along with the presence of certain cooperative locking means, securely maintains the doors and 25 bar in their closed and locked position with reference to each other and to the cylinder wall, while at the same time allowing the doors and bar (or bars) to be moved or swung 30 to that position where the cylinder opening is free of all obstructions.

Such full open position may obtain, however, when and only when the doors are unlocked from the division bar and the latter 35 unlocked from the cylinder.

The invention is applicable to utilization in connection with wooden or metallic cylinders, but in the instant case it is shown in connection with the former; this, however, not 40 by way of limitation.

One embodiment of the invention is shown in the accompanying drawings wherein:

Figure 1 is a front elevation of so much of a cylinder and two adjacent doors, and 45 the intermediate hinged division bar which

cooperates with the doors, as is necessary to an understanding of the structure;

Figure 2 a vertical sectional view taken on the line II—II of Fig. 1, with the door and division bar in both of these figures being 50 shown in locked relation with reference to each other and to the cylinder;

Figure 3 a vertical sectional view similar to Fig. 2, with the door and division bar in their fully opened position;

Figure 4 a sectional elevation of the latching and locking means employed in conjunction with the doors and the division bar, the parts being in the position shown in Fig. 3, and the door latches being precluded from 60 entering the opening in the division bar;

Figure 5 is a transverse sectional view taken on the line V—V of Fig. 1, with the door latches shown in locking relation with the pivoted division bar;

Figure 6 a detail perspective view of one 65 of the door latches;

Figure 7 a perspective view of the lower ends of the division bar and the cooperating keeper for its locking bolt;

Figure 8 a perspective view of such bolt; 70 and

Figure 9 a perspective view of one of the door latches.

In the drawings, 1 denotes the cylinder 75 body. Between two longitudinally extending ribs whereof, as 2 and 3, there is left an opening for the introduction and withdrawal of material, which opening is designed to be closed by a plurality of doors. Two doors, or 80 the ends of two doors, as 4 and 5, are shown in the instant case, it being understood that any number of doors may be utilized and a division bar 6, which will be hereinafter described in detail, placed between the adjacent 85 ends of each pair of doors.

The hinges for the doors are alike in form throughout except as they are right and left hand as the case may be, hence a description of one will suffice and similar parts upon 90

the other or companion hinge will be similarly numbered with the exponent "a" applied thereto.

It will, of course, be understood that the 5 ends of the doors at the ends of the opening adjacent the cylinder head may have any form of securing means cooperative with that element or with the heads, but inasmuch as such forms no part of the present invention, 10 I have not deemed it necessary to illustrate the same.

The door 4, which is arcuate in outline or formed upon the same radius as that of the cylinder, has secured to it, adjacent its end, 15 a hinge element or strap 7, the cooperating butt 8 whereof is rigidly affixed to the cylinder body adjacent the upper margin of the opening formed in the cylinder wall.

The door adjacent the lower end of the 20 hinge is cut away, as best shown in Figs. 4 and 5, to receive the inwardly projecting portion of the hinge strap 7 in which a transversely sliding latch 9 is mounted, said latch being normally projected outwardly to one 25 side of the hinge toward the division bar 6 through the action of a spring 10 which encircles a stem 11 extending from the rear portion of the latch and abutting a fixed stem guide 12 projecting inwardly of the hinge 30 structure.

As will be seen upon reference to Figs. 1 and 9, latch 9 is provided with a finger opening as 13 and with a stop 14, the latter extending upwardly into an opening 15 formed 35 in the hinge strap 7. Said opening 15 is above opening 13 and is of such length, in the direction of the movement of the latch, that the operator may readily draw the same from locking relation with the adjacent portion 40 of the division bar. Stop 14 prevents the latch from being projected too far, or in other words holds the latch in its proper position when projected outwardly by its spring 10.

Division bar 6 is connected to a butt 16 and, 45 as will best be seen upon reference to Figs. 1, 2 and 3, its pintle or pivotal connection 17, while standing parallel to the pivotal or pintle connections 18 of the doors 4 and 5, is below and to the front of the pintles 18.

The outer face of the division bar is recessed adjacent each side thereof to receive the overlapping straps 7 and 7a of the door hinges, and adjacent its lower end it is provided with a transversely disposed opening or recess 19, the upper wall 20 whereof cooperates with the latches 9 and 9a to hold the doors 4 and 5 in their locked position with reference to this division bar.

The extreme lower end of the division bar 50 is provided with a head 21, inner faces 22 whereof are inclined and designed to make a wedging fit with a corresponding recess formed in a keeper 23 secured to the lower 55 wall or margin of the opening. A sliding

bolt 24 is mounted for movement longitudinally of the lower end of the division bar, the bolt extending outwardly through the head and when the bolt is projected, cooperating with the keeper to lock the bar in its closed position, as shown in Figs. 1 and 2.

The bolt 24 is provided with a limiting stop or guide 25 extending laterally therefrom and through an opening formed in the body of the division bar.

The bolt 24 also has secured to its inner end a transversely extending bar or head 26 which lies within the opening 19 and is movable back and forth therein as the bolt 24 is moved outwardly or inwardly.

As will be best seen upon reference to Fig. 7, that wall of the opening 19 which is formed in the bar 6 which lies nearest the outer end of the bar is cut away as at 27 in order to form finger recesses into which the operator 35 may readily pass his finger and engage the crossbar 26 when it is desired to withdraw the bolt 24 from its locking engagement with the keeper.

Such retraction of the bolt 24 cannot, however, take place so long as either one or the other of the latches 9 extends into the opening 19, as the parts are so positioned and proportioned, that when the latches 9 are in engagement with the bar 6, or in other words 95 lie beneath the element 20, the bar 26 cannot be moved inwardly to withdraw the bolt 24. The bolt 24, or more specifically its crossbar 26 forms an interfering stop for the latches 9 when the bolt is moved inwardly, and the 100 bar 26 is likewise moved inwardly of the opening 19. Thus, as will be seen upon reference to Fig. 4, the latches 9 and 9a will be held outwardly by the bar 26 and the springs 10 held under compression, thereby preventing either of the latches 9 or 9a from passing under and in engagement with the member 20. 105

It will also be seen upon reference to both Figs. 3 and 4, that by reason of the fact that the pintles 17 and 18 are out of alignment 110 although parallel, the latches will be precluded from passing into the opening 19 as the doors and bar are thrown out of alignment, thus preventing registry of the latches 9 with the opening 19. Moreover, the bar 26 stands in the position shown in Fig. 3, and blocks the passage of the latch or latches into the opening 19 and into locking interengagement with the element 20 of the division bar.

It will be readily appreciated that when the division bar is brought down to closed position and locked by moving the bolt 24 home, the bar will, by reason of the beveled faces 22 and the similarly formed faces on 125 the keeper 23, draw the parts together into close relationship and, further, when the doors are moved downwardly the latches will lock the doors to the bar and consequently in closed position with reference to the cylinder.

der. In this way the structure as a whole is tied together and becomes quite rigid.

The doors, moreover, may be lowered one by one without fear of their becoming interlocked, and no undue strain is placed upon the operator, as would be the case if the doors were interconnected through the hinged division bar when and after the doors and bar were thrown upwardly into their open position. By having the division bar as well as the doors hinged and freely movable into open position, the opening in the cylinder will be clear from one end to the other of any obstruction which would preclude the easy introduction or withdrawal of the material undergoing treatment.

As above noted, by the employment of a bolt which cooperates with the door latches to hold said latches out of locking engagement with the division bar until the bolt has been moved home and the bar locked in place with reference to the cylinder, the doors cannot be locked to the division bar at any other time. With such arrangement it is not essential that the pivotal points of the adjacent doors and the intermediate division bar be in alignment. That arrangement however is preferred.

What is claimed is:

1. In combination with a cylinder having an opening formed therein for the introduction and withdrawal of material, a plurality of doors; a division bar intermediate the adjacent ends of the doors, said doors and bar being independently hinged to the cylinder at a margin of the opening formed therein, the pivots of the doors aligning and the pivot of the bar being parallel to but out of line with the door pivots; and a latch carried by each door adjacent the free marginal portion thereof, said latches standing in alignment with an opening formed in the normally free end of the division bar for locking engagement therewith when the bar and one or both of the doors are moved to closed position, said latches by reason of the offset position of the door and bar pivots being precluded from entering into cooperative locking relation at other positions of the parts.

2. The structure as set forth in claim 1, wherein means is provided for locking the free end of the division bar to the cylinder.

3. In combination with a cylinder having an opening formed therein for the introduction and withdrawal of material, a plurality of doors; a division bar intermediate the adjacent ends of the doors, said doors and bar being independently hinged to the cylinder at a margin of the opening formed therein; and means for independently interlocking each of said doors to the bar adjacent its free end, said means being inoperative to engage the bar when the doors are in a position other than wholly closed.

4. In combination with a cylinder having an opening formed therein for the introduction and withdrawal of material, a plurality of doors each hinged to the cylinder at the same margin of the opening, the pivotal connections being in substantial alignment; a division bar located between adjacent ends of said doors, said bar being likewise hinged to the cylinder adjacent the margin aforesaid, the pivotal connection of the bar lying parallel to but out of line with the pivots of the doors; and latches carried by each door cooperating with the bar to lock either one or both of said doors to the bar when and only when the doors are brought to their closed position.

5. In combination with a cylinder having an opening formed therein for the introduction and withdrawal of material, a closure for said opening, said closure consisting of at least two doors; and a division bar intermediate the adjacent ends of said doors, said doors and bar being hinged to the cylinder adjacent the same marginal edge of the opening; a lock carried by the free end of the bar for engagement with the cylinder; and a latch carried by each door, said latches engaging the bar and being held out of locking engagement with the bar until the lock carried by the bar is brought into locked position with the cylinder.

6. In combination with a cylinder having an opening formed therein for the introduction and withdrawal of material, a plurality of doors each hinged to the cylinder at the same margin of the opening, the pivotal connections being in substantial alignment; a division bar located between the adjacent ends of said doors, the pivotal connection of said bar being out of alignment with that of the doors whereby the doors and bar will swing through different arcs as they are moved to their open or closed position with reference to the cylinder; means for locking the division bar to the cylinder; and means for locking each of said doors to the division bar independent of each other when the bar is locked and the doors are brought to their closed position, said door locking means being inoperative to engage the bar at other positions of the parts owing to the different paths of movement through which the doors and bar pass in the opening and closing thereof.

7. In combination with a cylinder having an opening formed therein for the introduction and withdrawal of materials, a plurality of doors each hinged to the cylinder at the same margin of the opening, said doors swinging through a common path in their opening and closing movements; a division bar located between the adjacent ends of said doors and normally lying in a plane common to said doors when the parts are in closed position, said bar being likewise hinged to the

cylinder adjacent the margin aforesaid, said bar when shifted swinging through a path different from that of the doors, whereby when the doors and bar are swung toward open position the free end of the bar will be thrown out of alignment with the adjacent portions of the doors; and locking means carried by the doors and the bar normally cooperative when the doors and bar are moved to closed position, said locking means being precluded from operating, by non-alignment of the parts, when the doors and bars have been disengaged from their locked relation and moved toward or into open position.

8. A structure such as set forth in claim 7, wherein means is provided for locking the free end of the division bar to the cylinder.

9. In combination with a cylinder having an opening formed in the curved wall thereof for the introduction and withdrawal of material; a plurality of arcuate shaped doors hinged to the cylinder at one margin of said opening; a division bar likewise hinged to the cylinder adjacent said margin and between said doors, the pivotal connection whereof is out of line with that of the doors, said bar having the same arcuate shape as that of the doors; means for locking the bar to the cylinder when the bar is swung to cylinder closing position; and means carried by each door and cooperative with the bar to lock the bar and doors together when, and only when, the doors and bar are in cylinder closing position.

10. A structure as set forth in claim 9, wherein the locking means carried by each door and cooperative with the bar comprises a bolt mounted upon each door and movable into an opening formed in the adjacent end of the division bar.

11. A structure as set forth in claim 9, wherein the means for locking the bar to the cylinder acts as a stop to prevent the door locks from functioning until the bar locking means is moved to bar locking position.

12. In combination with a cylinder having an opening formed in the curved wall thereof for the introduction and withdrawal of material; a plurality of doors hinged to the cylinder at one margin of said opening; a division bar likewise hinged to the cylinder adjacent said margin and between said doors; a lock carried by the free end of the division bar; a keeper mounted upon the cylinder and cooperative with the lock of the division bar to hold said bar in its closed position when the bar is swung downwardly; means carried by each door and cooperative with the bar to lock said doors and bar together; and means carried by the bar lock for preventing the door locks from being moved

to locked position until the bar lock has been preliminarily moved to its locking position.

13. A structure as set forth in claim 12, wherein the pivotal connections of the doors to the cylinder are in alignment, and the pivotal connection of the division bar lies parallel to but out of alignment with the pivots of the doors, whereby when the parts are thrown to their open position the door locks will be prevented from engaging with the division bar.

In testimony whereof, I have signed my name to this specification.

THOMAS J. POWER.
